SOUND TRANSMITTING SYSTEM

Ernst Kammerer, Berlin-Tempelhof, Germany,
assignor to Klangfilm G. m. b. H., Berlin, Germany, a corporation of Germany

Application August 3, 1935, Serial No. 34,516
In Germany July 14, 1934

3 Claims. (Cl. 179—100.1)

In sound transmission equipment such as sound picture recorders or reproducers, it is desirable that the recorded or reproduced sound be checked by control means mounted at the sending end. The apparatus most extensively used for this purpose comprises a check-up or monitoring loudspeaker. The energy required for the monitor loudspeaker is usually derived from the amplifier feeding the main loudspeaker. It is known in this connection that the monitoring loudspeaker may be united with the same amplifier stage, either in parallel or in series relation to the main loudspeaker.

In the operation of such apparatus, however, a number of difficulties arise. The monitoring loudspeaker is often mounted in a room having acoustic conditions or properties which are unfavorable due to undesirable and disturbing noises. A situation like that prevails, for instance, in the projector booths in sound-film theaters where the projector machines produce marked noises. Now, it has been found that in such places the monitor loudspeaker is difficult in low or subdued passages of the sound and that the secondary noises of the room mask it so that auditory (aural) check-up is under certain circumstances impossible or at all events unreliable.

Fundamentally speaking, it would, of course, be feasible to feed the monitor loudspeaker with more energy compared with the main loudspeaker so that it would turn out to be sufficiently loud during low passages; but this would be attended with the drawback that, on the one hand, the monitor loudspeaker would be unnecessarily loud during loud passages and might fill a small transmitter room with sound almost to a point where this would be unbearable or uncomfortable, while, on the other hand, the energy of the main loudspeaker would be diminished to a point where the latter turns out to be too low.

The purpose of the present invention is to create an arrangement adapted and designed to render conditions so that the monitoring loudspeaker, also during low or subdued passages will be adequately loud even in rooms where there is a lot of noise, while yet not causing unbearably large acoustic energies at loud passages. Incidentally the rendition of the sound by the main loudspeaker should not be diminished, while in addition overmodulation of the tube feeding the monitoring device should be avoided.

According to this invention, the monitoring loudspeaker is fed by way of a distinct amplifier tube, the latter being inserted, for instance, in the plate circuit of the main loudspeaker power

tube so that its amplification is multiplied by the amplification (gain) of the power tube of the main loudspeaker.

According to another object of this invention, an amplifier tube is provided for cooperation with the monitoring loudspeaker whose amplification factor exceeds that of the main loudspeaker tube. In this instance, the monitoring loudspeaker tube could be modulated from the amplifying stage whence also the main loudspeaker tube is controlled.

In the case of using tubes of like gain for the main loudspeaker and the monitor, the identical effect is provided by coupling the tube of the monitoring loudspeaker with the amplifier only by the aid of such circuit means as will raise the amplification, for instance, the monitoring loudspeaker tube is connected with the amplifying loudspeaker stage which exercises a controlling action on the main tube by way of a step-up transformer. Instead of the latter circuit means insuring a corresponding effect such as tubes connected in suitable circuits may be used.

In the case of arrangements of this kind the danger of overmodulation of the monitoring loudspeaker tube is always very serious. Hence, according to a further object of this invention, distinct circuit means are provided for the coupling of the monitoring loudspeaker with a view to precluding over-modulation, the said protective means being preferably automatic in action, and they may be designed to act as current or voltage limiters. In suitable circuit schemes, resistances may be used therefor, the said resistances being of a nature so that by virtue thereof they will stabilize or practically stabilize the current. Resistances adapted for this purpose, such as iron-hydrogen resistances are known.

The invention will be better understood from the following description when considered in connection with the accompanying drawing, and its scope will be pointed out in the appended claims.

Referring to the drawing:

Fig. 1 is a wiring diagram of an arrangement wherein the monitor speaker supply tube is energized from the plate circuit of the main speaker supply tube.

Figs. 2 and 3 are similar diagrams of modified arrangements wherein the main and monitor loud speakers are energized through parallel circuits, and

Fig. 4 illustrates a modified arrangement including means for preventing over-modulation of the monitor speaker.

In the arrangement of Fig. 1, the input stage 1 is associated with the power tube of an ordinary amplifier by way of resistance and capacity. The main loudspeaker is connected at 3 by way of a transformer 4 in known manner. According to the invention, the plate circuit of the amplifier tube 2 contains another amplifier tube 5 which by way of the condenser 6 is in coupling relationship with the tube 2, and which by the intermediary of the transformer 7 as known in the prior art, feeds a monitoring loudspeaker which is connected at 8. Below the power or end-stage tube 2 any desired number of amplifying stages may be provided. The power stage may consist also of two push-pull connected tubes. Instead of one monitoring loudspeaker 5 also several such devices could be provided. The tube feeding the monitoring loudspeaker may have any desired characteristic since it in no way controls the operation of the main speaker.

Another embodiment of the invention is shown in Fig. 2. Connected with the input stage 1 of a standard amplifier by way of resistance 9 and condenser 10 is the power tube 11 feeding the main loudspeaker while, as known in the prior art, the main loudspeaker is connected at 12. Connected with the same input stage 1 by way of capacity 13 is the power tube 14 feeding the monitoring loudspeaker, and with the same tube 30 is joined at 15 the monitoring loudspeaker. According to this invention, the gain of the tube 14 of the monitoring loudspeaker is higher than that of the tube 11 feeding the main loudspeaker.

Fig. 3 illustrates another embodiment of the invention in which the power tube of the main loudspeaker and the monitoring loudspeaker may have the same relation as to amplification. Connected with the input stage 1 by way of resistance 9, capacity 10, as in Fig. 2, is the main loudspeaker tube 11, and associated with the latter at 12, as known in the earlier art, is the main loudspeaker. The coupling of the monitoring loudspeaker tube 16 is effected by way of capacity 13 and the transformer 17 provided according to this invention, the latter being so proportioned that it will step-up the voltage. The monitoring loudspeaker is connected at 15. What happens as a result of the connection of the transformer is

that the amplification of tube 16 is raised to a value above that for tube 11. For this purpose may be used also other suitable electric circuit means.

Fig. 4 shows a circuit organization designed to preclude the chances of overmodulation of the monitoring loudspeaker tube. Connected with the input stage 1 of a standard amplifier by way of resistance 9 and capacity 10, is the main loudspeaker power tube and with the latter, in turn, at 12 the main loudspeaker. In the plate circuit of the main loudspeaker tube 11 is included the monitoring loudspeaker tube 18 with connection of the monitoring loudspeaker at 19. The coupling of the monitoring loudspeaker tube is effected by way of the condenser 20, and a voltage divider comprising resistance parts 21 and 22. The resistance 21 is of the iron-hydrogen type designed to stabilize the current completely or practically so with the result that overmodulation of the tube will be avoided inasmuch as the control voltage is unable to exceed a definite value to be chosen in conformity with the modulation data of the tube.

In lieu of the iron-hydrogen resistor, a uranium lamp or the like may be employed. However, with a view to precluding over-modulation, recourse may be had also to other suitable amplitude-limiting means. Instead of one loudspeaker it is feasible to use a plurality of loudspeakers both for the main work as well as for monitoring.

Having now described my invention, I claim:

1. A sound-transmitting system including a main loudspeaker and a monitoring loudspeaker, an amplifier for actuating the main loudspeaker, a driving amplifier for actuating said first amplifier, and an amplifier having a higher gain than the first of said amplifiers connected to said driving amplifier for actuating said monitoring loudspeaker.

2. Apparatus as defined in claim 1 including means for preventing over-modulation of the amplifier actuating said monitoring loudspeaker.

3. Apparatus as defined in claim 1 including an iron-hydrogen resistor for preventing over-modulation of the amplifier actuating said monitoring loudspeaker.

ERNST KAMMERER.
